UNITED STATES PATENT OFFICE.

JASPER WHITING, OF BOSTON, AND PHILIP WADSWORTH, OF MILTON, MASSACHUSETTS.

CONTAINER.

Application filed May 19, 1921. Serial No. 470,858.

REISSUED

To all whom it may concern:

Be it known that we, JASPER WHITING and PHILIP WADSWORTH, citizens of the United States, residing, respectively, at Boston, county of Suffolk, and State of Massachusetts, and at Milton, county of Norfolk and State of Massachusetts, have invented a new and useful Improvement in Containers, of which the following is a specification, like reference characters on the drawings indicating like parts in the several figures.

This invention relates to containers which are designed to be tightly closed, such as cans, boxes, trunks, vaults, and similar enclosures. In containers of this type as ordinarily made, and especially those having hinged covers, it is difficult to make an air tight closure at the opening in the container. At the same time such a closure is desired for many purposes, particularly when the container is to be used to store materials that would be injured by moisture, dust, vermin, etc., or which contain a volatile element that would escape unless the materials were kept in an absolutely tight enclosure. Such a container also is desirable for holding materials such, for instance, as tobacco, cigars, and the like, which should be kept in an atmosphere of relatively constant humidity.

With these considerations in view, it is the chief object of the present invention to devise a container of the general character indicated which will have an air tight closure that can be moved readily to open the container or to close and seal it again. It is also an object of the invention to devise an article of this general character which can be economically manufactured and which shall be of sturdy and substantial construction.

The nature of the invention will be readily understood from the following description when read in connection with the accompanying drawings, and the novel features will be particularly pointed out in the appended claims.

Referring now to the drawings,

Figure 1 is a view partly in front elevation and partly in vertical cross section, showing a container constructed in accordance with this invention; and

Fig. 2 is a cross sectional view on the line 2—2, Fig. 1.

The construction shown comprises a sheet metal box, the lower or body portion of which is designated at 2. The upper part of each wall of this box is folded over, as indicated at 3, to form a horizontal shoulder 4. Below this shoulder the metal is bent 50 toward the wall or side of the box and is soldered thereto at 5.

The cover 6 of the box is of the usual construction except that the central portion of the cover is preferably depressed as indicated at 7, and this cover is hinged to the rearward side of the box at 8, Fig. 2. When the cover is in its closed position the lower edge of its downwardly turned margin may rest on the external shoulder 4 of the box, and means is provided to draw this cover firmly down on the shoulder. In the construction shown a fastening means of the toggle type has been used for this purpose.

This fastening device comprises a U-shaped metal strap 10 pivoted to the front edge of the cover at 11, and also pivotally connected by means of a pin 12 to a handle or lever 13 having a point or toe 14 to enter a recess 15 formed in a bracket 16 that is riveted to the front of the box. This device is shown in Fig. 2 holding the cover in its closed position, and it will be seen that when the handle 13 is swung toward the left it will pivot on the point 14, thus causing the pin 12 to swing upwardly and thereby release the cover. A swinging movement of the handle in the opposite direction operates through these parts to exert a powerful closing movement on the cover. No novelty, however, is claimed in this particular fastening means and it may be replaced by any other suitable fastening device.

It will be observed that the cover 6 does not close the top of the box tightly, and for the purpose of performing this function a closure plate or inner cover 18, preferably made of resilient material such as sheet steel or brass, is secured to the central depressed portion 7 of the cover 6 by means of bolts 19—19. When the cover is closed the margin of this plate 18 overlies the edge 3 of the open top of the container and this marginal part is preferably grooved to receive a gasket 20 made of rubber, cork, or any other suitable material. This gasket preferably is cemented in the groove in the margin of the plate 18. The heads of the bolts 19—19

are soldered to the plate 18 or tight joints are formed between these bolts and the plate in some other suitable manner.

It will now be evident that when the cover 6 is swung down into its closed position, the gasket 20 will engage the edge 3 at the top of the container or box 2 just before the cover reaches its lowermost or completely closed position. The elasticity of the plate 18 and the cover 6 will resist yieldingly the continuation of the closing movement of the cover, and as this movement is completed the marginal portion of the closure plate 18 will be sprung upwardly, as shown in the drawings, thus causing the plate to press the gasket 20 firmly against the upper edge 3 of the container and thereby make an air tight joint at this edge. If the cover 6 is made of resilient material, both the resiliency of this part and also that of the plate 18 will be utilized in pressing the gasket 20 firmly against the edge 3.

It will be seen that the depression of the central portion 7 of the cover provides ample space for the yielding movement of the plate 18 and the depth of this depression or offset may be made such that it will be impossible to spring the plate 18 far enough to permanently distort it. One or more shims 21 may be placed between the plate 18 and the depressed portion 7 of the cover to increase the range of movement of the marginal portion of the closure plate if desired. It will also be observed that the rearward edge of the opening in the top of the box is set inwardly by reason of the offset 22, Fig. 2, and that, due to this construction and the position of the hinge 8 relatively to the adjacent part of the edge 3, the gasket 20 will come into contact substantially simultaneously with all parts of the edge 3 so that an approximately uniform flexure of the entire margin of the plate is produced.

This invention thus provides a closure construction for containers and enclosures which is of very simple form, is economical to manufacture, and is very effective. The invention considered in its broader aspects may be embodied in many forms, each having its own advantages. For instance, the closure may be substantially rigid and be yieldingly held in its closed position, the resiliency of the cover being depended upon for this action, or, the closure itself may be resilient and the cover or other supporting means therefor may be rigid. In other constructions, also, both the closure and its support may be resilient. In some constructions the closure and cover may have a certain portion or portions in common. That is, the closure may consist of a marginal strip shaped to fit over the edge of the opening in the container and the central portion of the closure may be formed by the cover itself. The invention thus may be variously

modified and the design used in any individual case will necessarily be controlled as to some particulars by the nature of the container on which the closure is used.

What is claimed as new is:

1. A container having an opening therein, an outer cover for said opening, an inner cover attached to and abutting said outer cover within the marginal portion of the inner cover but leaving said marginal portion spaced therefrom, one of said covers being resilient, and means for holding said outer cover in its closed position with said inner cover closing said opening. 70

2. A container having an opening therein, an outer cover for said opening, a resilient inner cover attached to and abutting said outer cover within the marginal portion of the inner cover but leaving said marginal portion spaced therefrom, and means for holding said outer cover in its closed position with said inner cover closing said opening. 85

3. A container having an opening therein, a hinged outer cover for said opening, an inner cover attached to and abutting said outer cover within the marginal portion of the inner cover but leaving its marginal portion spaced therefrom, one of said covers being resilient, and means for holding said outer cover in its closed position with said inner cover closing said opening. 90

4. A container having an opening therein, a hinged outer cover for said opening, a resilient inner cover attached to and abutting said outer cover within the marginal portion of the inner cover but leaving said marginal portion spaced therefrom, and means for holding said outer cover in its closed position with said inner cover closing said opening. 100

5. A container having an opening therein, an outer cover for said opening, and an inner cover attached to and abutting said outer cover within the marginal portion of the inner cover but leaving said marginal portion spaced therefrom, one of said covers being resilient, said marginal portion being adapted to make a sealing contact with the edges of the opening when the outer cover is closed, and said outer cover being hinged to the container on a line offset laterally from the edge of the opening so as to produce an approximately uniform pressure on all the marginal portion of the inner cover when the outer cover is closed. 110

6. A container having an opening therein, an outer cover for said opening, a resilient inner cover having its margin spaced from said outer cover and being attached to and abutting said outer cover within said margin, said outer cover being hinged to the container on a line laterally offset from the edge of the opening. 120

7. A container having an open top, an 120

outer cover hinged to said container to swing into either an open or closed position, a resilient inner cover for closing said open top, said outer cover having a depressed central part attached to and abutting said inner cover within the marginal portion of the latter, said marginal portion being free to yield toward said outer cover, and means for holding said outer cover in its closed position, whereby the marginal portion of said inner cover is held yieldingly against the edge of said top. ¹⁰

In testimony whereof we have signed our names to this specification.

JASPER WHITING.
PHILIP WADSWORTH.
